(57) **CLAIM**

The ornamental design for a terminal for audio intercom system, as shown and described.

DESCRIPTION

FIG. 1 is a top perspective view of a terminal for audio intercom system showing my new design; FIG. 2 is a bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; and, FIG. 9 is a partial enlarged view taken from circle 9 in FIG. 1.

The dash-dash broken lines in the drawings illustrate the portions of the terminal for audio intercom system which form no part of the claimed design.

The dot-dash broken lines in the drawings are included for the purpose of illustrating the partial enlarged views.
